UNITED STATES PATENT OFFICE

167,090

CHILD'S TRICYCLE

George Edward Lines, Kingswood, England, assignor to Lines Bros. Limited, Merton, London, England, a British company

Application June 4, 1951, Serial No. 15,390
In Great Britain February 23, 1951

Term of patent 14 years

(Cl. D34—15)

To all whom it may concern:

Be it known that I, George Edward Lines, a subject of the King of Great Britain, resident of Pickwick, Warren Drive, Kingswood, Surrey, England, have invented, a new, original, and ornamental Design for a Child's Tricycle, of which the following is a specification, reference being made to the accompanying drawings, forming a part thereof.

In these drawings:

Figure 1 is a perspective view of a child's tricycle showing my new design;

Figure 2 is a perspective view of the opposite side thereof; and

Figure 3 is an enlarged fragmentary view thereof.

I claim:

The ornamental design for a child's tricycle, substantially as shown.

GEORGE EDWARD LINES.
